*J. H. Chandler,
Mortising Machine.
Patented Dec. 17, 1834.*

Dec 17. 1834

125.

John H. Chandler. Worcester, Massachusetts.

The Schedule referred to in their Letter Patent, and Making
part of the same containing a description and the words of the said
John H. Chandler, himself of his Improvement in the construc-
tion of machines for Mortising.

To all People whom these presents shall come.—
Doth know that I, John H. Chandler, of Worcester, in the
County of Worcester, and Commonwealth of Massachusetts, Mech-
anic, have invented a new and useful improvement in the
construction of Machines for Mortising, and that the following
is a full and exact description of the same as invented or
improved by me.—

The Machine heretofore used for making mortises, has been
attended with these difficulties. The piston or shaft holding the
chisel has been so imperfectly supported or guided, that it was
liable to be removed from its right position, thereby making
the mortise irregular or out of square, and in order to remedy
this evil, the piston has had to closely confined that the oper-
ation of the machine, has been greatly embarrassed by too great
friction. Another inconvenience has also arisen from the use
of common chisel, which leaves chips in the mortise, and
much time is required in removing them. all these inconveniences
are removed by constructing the machine after the manner
described by me which is as follows:

The frame of the machine may be constructed of wood or
iron, or any suitable material. My machine is partly of iron
and partly of wood. A plank of convenient dimen-
sions, composes the foundation of the frame. Near the front
end of the plank, are nailed three posts of wood, the
end of the two front ones, are hewed into the plank, but

the third one stands back between them, and is turned into it. The parts are firmly connected by rods, and plates or castings. There casting are of a triangular form, and connected to the parts at the angles. One of these arms is near the top, and the other is placed about one third of the distance from the top downwards towards the bottom. The front end of these triangular pieces of iron are circular, projecting out in front of the two front parts, a hole is made thro' each of them at the end, on the centre, as near the end as will answer. Through these holes passes the piston which holds the chisel in a socket at the lower end. The piston is moveable up and down through the holes made in the casting mentioned above. On one side of the piston, and half the length of it, is cut a groove. On the upper side of the lower plate or casting and directly back of the piston, is a spring, the back end of which is made fast to the casting, the other end is made forked, the legs of the fork passing each side of the piston. Directly beneath the foot of this spring, is an iron ring passing round the piston, and on the inside of it, is a tooth, or projecting piece of iron fitted to stand in the groove in the piston. This ring has two stems or handles attached to it, for the purpose of turning the piston. The ends of the handles as they pass round under the spring, are made to fall into a notch on the right hand side of the casting. A little below the lower casting is a hole into the part a square hole for the purpose of running a screw below this. This screw on the plank is another to assist in holding the parts together and confining them to it. In front of the feet of the two front parts, is firmly confined a plank resting upon, and attached to the foundations of the frame or machine, by means of a bolt. Upon this board pieces of iron are placed parallel to each other and connected together with plates and screws to confine them. On the back side is mounted a stand extending up to the rear, passing through the narrow

and mentioned above and confined to it. passing through the foundation, crop piece and steel, on the right hand side, and associated with it to confine it at pleasure, is, an iron holder with a head, on the front side of it. Back of the third part, are firmly set two short standards, with a space between them. In this space is fastened a pivot, the lower end of a shaft, which extends up somewhat higher than the part, is in the centre and directly underneath the crop piece, is firmly set a tenon, attached to this at the end in a mortise, by a pin. is, a lever with a handle turned on the end of it, near the end of this lever towards the machine, is fastened by a hinge, another shaft of the same size and height of the other. From the top of this shaft downwards, are mounted at short distances apart five holes, attached to the upper end of this shaft, is another lever, by means of mortises and pins at the end, on the inner side of this lever, and at a short distance from the front end, is placed a hinge, to which is attached the upper end of the piston. This lever is movable up and down on the five holes. The chisel is accommodated with two lips which, in addition to making the sides of the mortise smooth, does by prizing the chips between them, bring them out of the mortise. The machine may be operated, upon a common work bench, it being confined to it by means of a belt.

Explanation of the drawing

- A. Back or foundation of the machine. B. Crop piece. d. d. two front parts. I. Part back of the two front ones. K. triangular piece of iron, for connecting the parts, and guiding the piston. m. m. another similar piece for the same purpose. o. end of the forked spring. t. winding with a stem or handle for turning the piston. o. e. piston holding the chisel. y. y. groove in the piston. g. holder to prevent the piston while mortising, from rising. p. Standard mounted at the top by the screw. q. a. chisel inserted into the lower end of the piston and slides between which the piece to be mortised, is placed. r.

Standards inserted into the front of the machine, the upright shaft moves in a pin at X, the upper lever moves in a pin at each end in front shaft W, this is connected by a pin to the lever V, with the pin K, a bolt or screw to confine the machine to the back of the handle of the lever.

Operation of the Machine.

The operator takes the piece to be mortised in his left hand, and lays it on the cross piece on the left hand side of the piston box, and the two slides are then with his right hand takes hold of the lever W, at the handle V, and by raising it, the piston being connected to it by a hinge and the upper lever K, to the shaft K, by a pin and the piston being connected to the lever, advanced also, the lever W is the piece under the chisel where the mortise is to be made, he then adjusts the slides and standard, by confining them with the screws in such a position as will bring the chisel exactly between the gauge strokes of the mortise, he then brings his hand against the standard, to feed the chisel, and then bears down upon the lever at V, and the chisel is made to cut down the depth required, and by means of the lips or lateral edges of the chisel, the chips are brought out of the mortise, this operation is repeated until the mortise is obtained to the desired point in one direction, when the operator turns the piston half round and with it the chisel, to present the chisel in a proper manner for the other end of the mortise, the operator is prepared by taking hold of the handle, in the ring which before moves the piston, and carrying it round to the opposite side where it falls into a notch in the triangular cutting K, and is confined in its proper position by the lips of the forked spring C, the piston is now moved by the stem or handle L, by means of the tooth attached to the inside of the ring, and being on the groove of the piston, all I do, as my invention or improvement, is the groove in the piston, with the forked spring, and ring with tooth and

handle fortuning it, with the application also of a chisel
to the lateral edges.

In testimony that the above is a true spe-
cification of my said improvement, I have caused to my
hand this twenty ninth day of August, one thousand eight
hundred and thirty four,

Witness,

Chas. G. Baldwin
J. J. Hornsworth
Ch. Whelock
